1 Claim (Cl. 72—63)

ABSTRACT OF THE DISCLOSURE

In a hydraulic forming press for sheet metal blanks having a pressure chamber body with a bore therethrough that is closed near its bottom by a resilient cup-shaped diaphragm and having a forming tool beneath the diaphragm which is adapted to enter the bore, a ring closely surrounds a reduced diameter lower portion of the diaphragm. The ring has a coplanar bottom surface engageable with an upwardly facing surface on the forming tool. The ring accommodates radial play of the forming tool relative to the bore in the body and prevents intrusion of the diaphragm into the space between the forming tool and the pressure chamber body.

This invention relates to hydraulic presses for forming sheet metal blanks, and refers more particularly to hydraulic forming presses of the type comprising a pressure chamber body with a vertical bore therethrough that is closed near its bottom by a resilient cup-shaped diaphragm, and a forming tool beneath the diaphragm which is adapted to enter the bore and against which a sheet metal blank can be formingly pressed by pressure fluid confined in the bore above the diaphragm and exerting force through the diaphragm.

In hydraulic presses of the character described the forming tool usually comprises a central punch which is fixed on the press table and has an upwardly projecting forming portion, and a blank holding ring which encircles the punch and has a flat upper surface. The pressure chamber body, in the bore of which a resilient cup-shaped diaphragm is so secured as to be confined against bodily axial motion, is movable upwardly and downwardly relative to the punch and the clamping ring.

When a sheet metal blank is to be formed, it is placed on the clamping ring, and the pressure chamber body is lowered to cause the marginal edge portion of the blank to be clamping confined between the diaphragm and the clamping ring. While maintaining clamping force upon the marginal portion of the blank, the pressure chamber body continues to descend in unison with the clamping ring, and as the fixed punch upwardly displaces the central portions of the blank and diaphragm, fluid under pressure in the pressure chamber body, acting through the diaphragm, acts upon the blank to form it to the shape of the forming tool.

In order to obtain clamping relationship between the diaphragm and the blank holding ring of the forming tool, the blank holding ring must enter the lower portion of the bore in the pressure chamber body as the latter moves down. This requires that there be a certain clearance between the forming tool and the bore surface in order to insure that they do not bind, and such clearance must be great enough to allow for variations in working temperature of the parts.

Heretofore the useful life of the cup-shaped diaphragm in such a press has depended upon the closeness of fit between the forming tool and the bore in the pressure chamber body, because the diaphragm, under the high pressures to which it is subjected in forming operations of this type, becomes almost plastic, and the material

2

of the diaphragm therefore tended to penetrate into any space that existed between the blank holding ring and the bore surface of the pressure chamber body, with the result that the diaphragm was more or less gradually crumbled. In order to prolong the useful life of the cup-shaped diaphragm, which is relatively expensive, the prior practice has been to machine the forming tool and the bore in the pressure chamber body to fit one another as closely as possible. The accurate machining of these parts was relatively expensive, and to some extent economy in diaphragm life was achieved at the sacrifice of economy in machining the bore and forming tool. But even close machining could not overcome the problem created by changes in temperature of the parts. Furthermore, when the forming tool and pressure chamber body bore were made to fit one another with very small clearance, extreme care was required in assembling the forming tool on the press to insure that it was accurately centered with respect to the bore. In view of these difficulties, it was not possible in practice to achieve such an accurate fit between the forming tool and the bore in the pressure chamber body as to obtain a satisfactorily long useful life of the diaphragm.

With the foregoing considerations in mind, it is a general object of this invention to provide means in a hydraulic forming press of the character described for providing its cup-shaped resilient diaphragm with a satisfactorily long useful life while at the same time obviating the need for obtaining a close and precise fit between the forming tool and the bore in the pressure chamber body.

Thus it is a general object of this invention to achieve substantial economies in the operation of a hydraulic press of the character described by prolonging the useful life of its diaphragm and by also reducing the cost of machining the forming tool and pressure chamber body.

Another object of the present invention is to simplify the mounting of the pressure chamber body and forming tool in a hydraulic press of the character described, while at the same time prolonging the useful life of the diaphragm, by the provision of inexpensive means that makes possible a comparatively loose fit of the forming tool in the bore of the pressure chamber body, so that the tool and body need not be accurately centered relative to one another, such loose fit also eliminating the risk that the tool and body will bind in one another and thereby assuring safe functioning of the press.

A further and more specific object of this invention is to achieve substantially reduced costs in the operation of a hydraulic forming press by the provision of a simple, inexpensive and easily replaced ring which encircles the lower portion of the cup-shaped diaphragm in such a press and projects a small distance below the diaphragm, said ring being axially displaceable to some extent but being retained against bodily axial displacement out of the bore in the pressure chamber body by cooperating means on the ring and on said body, and said ring having a bottom surface which can engage the top surface of the forming tool with a close fit to accommodate play between the forming tool and the pressure chamber body while also preventing the diaphragm from intruding into the clearance space between them.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates one complete example of the physical embodiment of the invention constructed according to the best mode so far devised for

the practical application of the principles thereof, and in which:

FIGURE 1 is a fragmentary view, partly in side elevation and partly in vertical section, of a hydraulic forming press embodying the present invention; and

FIGURE 2 is a fragmentary vertical sectional view on an enlarged scale of a portion of the press structure shown in FIGURE 1.

Referring now to the accompanying drawing, the numeral 5 designates generally the working portion of a hydraulic press, comprising a mounting plate 6 which is adapted to be fastened to a press head, a pressure chamber body 7 which is suspended from the mounting plate 6 for relative up and down motion and which has a vertical bore 8 therethrough, a cup-shaped diaphragm 9 which is secured in the lower portion of the bore 8, and a forming tool 10 which is carried by a press table 11 beneath the pressure chamber body 7.

The pressure chamber body 7 is mounted for up and down motion relative to the plate 6 by means of a plurality of long bolts 12 which have their heads lowermost and which extend upwardly through holes in radially outwardly projecting flange means 13 on the pressure chamber body, near the top thereof, and have their threaded upper end portions engaged in vertically aligned threaded holes in the plate 6 and secured by lock nuts 14. A helical compression spring 15 is confined between the head of each bolt and the flange means 13 thereabove, to provide yielding support for the pressure chamber body.

The cup-shaped resilient diaphragm 9 is secured in the bore 8 in the pressure chamber body, with its bottom spaced a small distance above the lower end of the bore and with its circumferential side wall 16 projecting upwardly and providing a seal around the bore. To confine the diaphragm against bodily axial motion relative to the pressure chamber body, the side wall of the diaphragm is formed with a radially outwardly projecting circumferential land 17 which is received in a mating groove 18 that extends around the bore. An expansion ring 19 inside the diaphragm side wall, radially opposite the land 17, maintains the land engaged in the groove 18 during operation of the press but is readily removable to provide for replacement of the diaphragm. The bottom wall 20 of the diaphragm has substantially flat, parallel top and bottom surfaces, and, although illustrated as being of unitary construction, it can be formed in three parts, for purposes of replacement economy, in accordance with the principles of the invention disclosed in the copending application of Hugo Moller, Ser. No. 458,673, filed May 25, 1965 and now Patent No. 3,334,504.

Cooperating with the diaphragm to define a pressure fluid chamber in the body 7 is a plunger 22 which is slidably received in the upper portion of the bore 8 and which has a spherically concave undersurface 23. As is conventional, the plunger is removably mounted on the press head (by means not shown) for up and down motion in the bore, by which fluid therebeneath can be placed under pressure. A venting duct 24, closed by a screw 25, extends through the plunger for bleeding air out of the pressure chamber as the same is filled with hydraulic fluid.

The plunger has a reduced diameter bottom portion which provides a circumferential recess in which there is received a resilient sealing ring 26 of U-shaped cross-section with its legs projecting downwardly. A rigid retaining ring or washer 27, secured to the underside of the plunger by means of screws 28, engages under the radially inner leg of the sealing ring to confine the sealing ring against axial displacement relative to the plunger. The sealing ring is so arranged that its radially outer leg engages the bore surface and is forced more snugly against the same as pressure is increased on the fluid beneath the plunger.

The forming tool 10 comprises a rigid stationary punch 29 which is attached to the stationary press table 11

and a blank holding ring 30 which encircles the punch. The blank holding ring has a flat upper surface and is mounted for up and down motion on pressure rods 31 that extend through guide holes 32 in the press table and are adapted to be acted upon by force exerting means (not shown) in such a manner that the blank holding ring can descend with the pressure chamber body while yieldingly resisting downward motion so as to react upwardly against the diaphragm and cooperate with it in imposing clamping force upon the marginal edge portion of a sheet metal blank 33. As the pressure chamber body and blank holding ring descend, the central portion of the diaphragm is displaced upwardly by the punch, and the force of pressure fluid in the pressure chamber, transmitted through the diaphragm, forces the blank into a shape conforming to that of the forming tool.

Although the forming tool comprising the blank holding ring 30 and punch 29 enters the lower portion of the bore 8 in the pressure chamber body during each forming operation of the press, it is a feature of this invention that the blank holding ring need not fit closely in the bore and, in fact, preferably fits it with a substantial clearance. Nevertheless the diaphragm is prevented from intruding into this clearance space by reason of the provision of a substantially rigid sealing ring 34 which encircles the lower portion of the diaphragm and projects a small distance beneath the same.

The sealing ring 34 is retained in the bore by operating retaining means on the ring and on the pressure chamber body, comprising a radially outwardly projecting circumferential land 35 on the sealing ring, defining a downwardly facing shoulder, and a land 36 on the pressure chamber body, projecting radially into the bore and extending circumferentially therearound at a distance above the bottom of the bore to provide an upwardly facing shoulder which engages the downwardly facing shoulder on the sealing ring. To provide the land 35 on the sealing ring, the sealing ring can have a step-wise reduced outside diameter, its upper portion being larger in outside diameter than its main body portion. To provide space for the sealing ring between the pressure chamber body and the diaphragm, the diaphragm has a reduced outside diameter at its bottom portion that defines a notch or recess 37 in which the sealing ring has a substantially close fit.

The sealing ring 34 has a flat coplanar bottom surface which cooperates with the flat upper surface on the blank holding ring, and since the sealing ring projects a distance below the bottom of the diaphragm and is free for a certain amount of axial movement to and from the position in which its land 35 engages the land 36 on the pressure chamber body, pressure applied to the diaphragm forces the sealing ring into intimate engagement with the top surface of the blank holding ring when the press is closed. As a result, the sealing ring 34 of this invention serves to bridge any radial play between the forming tool and the surface of the bore 8, while preventing the diaphragm from intruding into the radial space between them. Hence the forming tool can be made to fit the bore with a substantially loose fit and without the need for accurately maintained tolerances. It will be apparent that the sealing ring thus eliminates the need for special precautions with respect to centering the forming tool relative to the bore and accommodating variations in thermal expansion of the forming tool and pressure chamber body.

Installation of the sealing ring of this invention is relatively simple. With the plunger 22 and diaphragm 9 removed from the bore 8, the sealing ring 34 can be installed by merely inserting it axially into the bore from the top thereof until the land 35 on the sealing ring engages the land 36 on the pressure chamber body, after which the diaphragm 9 is similarly inserted into the bore 8 until its land or collar 17 engages in the groove 18

in the pressure chamber body. The diaphragm is then secured by the expansion ring 19.

It will be evident that the sealing ring 34 could be formed as a split ring, and that it could be retained in place by any of the several obvious equivalents of the particular land arrangements herein specifically disclosed for purposes of illustration, so long as it is allowed some degree of displacement by which it can be snugly engaged with the blank holding ring under downward force exerted by the diaphragm when the press is closed.

From the foregoing description taken together with the accompanying drawings it will be apparent that this invention provides simple, inexpensive and very effective means in a hydraulic forming press for prolonging the useful life of the resilient cup-shaped diaphragm in such a press while still allowing the forming tool and pressure chamber body bore to be formed with a substantially loose fit that facilitates and reduces the cost of machining and aligning them.

What is claimed as my invention is:

1. A hydraulic forming press of the type comprising a pressure chamber body having a downwardly opening bore therein, a forming tool beneath said body a portion of which is adapted to enter the lower portion of said bore, and a cup-shaped resilient diaphragm in said bore, 25 spaced above the lower end thereof, which closes the bore and cooperates with the body to define a pressure chamber above the diaphragm and which transmits the force of pressure fluid in said chamber to a blank therebeneath to form the blank to the shape of the forming tool, said forming press being characterized by:

- (A) the forming tool having a diameter smaller than that of said bore, to fit the bore with substantial radial clearance;
- (B) the lower portion of the diaphragm having a reduced outside diameter smaller than that of the

5

35

forming tool to define a downwardly facing circumferential shoulder on the diaphragm;

(C) a sealing ring in said bore closely surrounding said reduced diameter lower portion of the diaphragm said sealing ring

(1) having at its top a circumferential flange that projects radially outwardly and underlies said shoulder on the diaphragm, and which flange has an outside diameter to closely fit said bore, and

(2) having a coplanar bottom surface which is engageable with a circumferential upwardly facing surface on the forming tool; and

(D) a circumferential land on the pressure chamber body projecting radially into said bore near the bottom thereof and engageable by the underside of said flange on said sealing ring for holding the latter against bodily axial displacement out of the bore in the pressure chamber body so that the sealing ring can be confined between the diaphragm and the forming tool with the bottom surface of the sealing ring in snug engagement with said surface on the forming tool, whereby the sealing ring can accommodate radial play of the forming tool relative to the surface of said bore and can provide a seal around the diaphragm which prevents intrusion of the latter into the space between the forming tool and the pressure chamber body.
